MOISTUREPROOF CONNECTION FOR IGNITION SYSTEMS

Application filed May 5, 1932. Serial No. 609,437.

This invention relates to ignition systems for internal combustion engines and more particularly to the distributor and coil thereof and has for the primary object, the provision of means whereby the coil may form a cap or closure for the distributor adding to the compactness of the device and permitting the electrical connections between the distributor and coil to be shortened and completely protected against moisture or water, thus obviating short circuits and loss of electrical energy by the use of exceedingly long electrical conductors exposed to atmospheric conditions.

With this and other objects in view, this invention consists in certain novel features of construction, combination and arrangement of parts to be hereinafter more fully described and claimed.

For a complete understanding of our invention, reference is to be had to the following description and accompanying drawings, in which

Figure 1 is a side elevation illustrating a combined distributor and coil constructed in accordance with our invention and electrically connected to spark plugs.

Figure 2 is a vertical sectional view illustrating the same.

Figure 3 is a sectional view taken on the line 3—3 of Figure 2.

Figure 4 is a vertical sectional view taken on the line 4—4 of Figure 3.

Figure 5 is a detail sectional view illustrating the connection of a spark plug conductor to the distributor.

Figure 6 is a diagrammatical view illustrating the wiring diagram between the coil and distributor and the electrical source.

Referring in detail to the drawings, the numeral 1 indicates a distributor base in which is located the breaker assembly 2 including the usual rotor 3. A hollow body 4 of insulated material is removably mounted on the base 1 and has operating therein the rotor 3. The base 1 overlaps the body 4 to establish a moisture-proof connection between said parts. The upper end of the body is closed by a coil 5, the latter having a flanged portion overlapping a portion of the body to

establish a moisture-proof connection between the coil and body. The coil 5 includes the usual primary and secondary windings with one terminal of the secondary winding connected to a yieldable brush or terminal 6 extending into the body 4 to engage the rotor 3. Vertically arranged barrels 7 are formed integrally with the walls of the body and have located therein conductor sleeves 8, the lower ends of which receive terminal posts 9. One of the posts 9 is connected to a ground as shown in Figure 6 and the other terminal 9 is electrically connected to the breaker assembly, the latter being electrically connected to a battery or electrical source 10 which is connected by a conductor 11 to the ground. The coil 5 has a ground conductor 12 to which the secondary and primary windings are connected and the conductor 12 is provided with a terminal 13 and a corresponding terminal 14 is electrically connected to the primary winding of the coil. The coil 5 assembled on the body positions the terminals 13 and 14 in the conductor sleeves 8 of the terminals 9. Thus it will be seen that the electrical connections between the coil and breaker assembly of the distributor are housed and protected against moisture or atmospheric conditions, also providing extremely short electrical connections between said parts.

Offset portions 15 are formed on the body and terminate in angularly disposed and vertically arranged cup-shaped terminal sockets 16 provided with restricted throats 17. Electrodes 18 are embedded in the offset portions 15 with their inner ends extending into the body in close proximity to the path of movement of the rotor 3 while the outer ends of the electrodes terminate within the sockets 16 so that when high tension conductors 19 are inserted in said sockets as shown in Figure 5, the outer ends of the electrodes become embedded therein. The restricted throats 17 frictionally grip the insulation of said conductors and retain them in the sockets, thereby establishing an efficient electrical connection between the conductors and the electrodes and one in which moisture will be excluded from. Spark

plugs 20 are formed with sockets 21 similar in construction to the sockets 16 to receive the other end of the high tension conductors which also form moisture-proof connections between said conductors and the spark plugs. The electrodes of the spark plugs embed in the conductors similar to the electrodes 18.

While we have shown and described the 10 preferred embodiment of our invention, it will be understood that minor changes in construction, combination and arrangement of parts may be made without departing from the spirit and scope of our invention, 15 as claimed.

Having thus described our invention, what we claim is:—

1. In a device of the character described including a distributor base having a breaker assembly electrically connected to an electrical source and a rotor, an insulated body mounted on said distributor head with a moisture-proof connection therewith and having the rotor operable therein, electrodes 20 carried by the body to receive electrical current from the rotor and electrically connected to spark plugs, a coil closing the body and having a moisture-proof connection therewith, an electrical connection between 25 the coil and the rotor and confined in the body, detachable connections carried by the body with one of said connections connecting the coil to the breaker assembly and the other connection connecting the coil to a 30 ground, said connections being confined within the body and housed and protected from moisture thereby.

2. In a device of the character described including a distributor base having a breaker assembly electrically connected to an electrical source and a rotor, a body mounted on the base and receiving the rotor, extensions on said body and having angularly related cup-shaped portions forming terminal 40 sockets, electrodes embedded in said extensions and extending from the sockets to the interior of the body to receive electrical current from the rotor, said sockets having restricted throats, high tension conductors 45 received in said sockets and gripped by the throats with the electrodes embedded therein, said conductors connected to spark plugs, a coil closing said body, and electrical connections between the coil rotor and the 50 breaker assembly.

In testimony whereof we affix our signatures.

FRED R. DAGLEY.
ADRIAN W. GRANT.
